UNITED STATES PATENT OFFICE

2,446,634

LOAD SUPPORTING PALLET

Burton C. Coit, Jr., Washington, Pa., assignor to
 Tri-State Engineering Company, Washington,
 Pa., a corporation of Maryland

Application November 14, 1947, Serial No. 785,947

5 Claims. (CL 248—120)

1

This invention relates to pallets that are transportable by fork lifting trucks and are adapted for carrying loads either for transportation or for stacking in warehouses, in freight cars or the like.

My invention has for one of its objects the provision of a pallet structure wherein the legs are made of rods or heavy wire but which, nevertheless, have sufficiently extended bearing and supporting areas at their upper and lower ends to adequately support and brace the pallet deck and base, notwithstanding the relatively small cross-sectional area of the legs, throughout the major portion of the space between the deck and its base, this small cross-sectional area being useful in that it presents a minimum of obstruction to lifting forks.

Another object of my invention is to provide a pallet structure wherein mesh strips are employed for the base, with an improved manner for connecting the base strips that extend in one direction to the base strips that extend in directions generally crosswise thereof.

As shown in the accompanying drawings, Figure 1 is a fragmentary plan view of the pallet; Fig. 2 is a side view thereof; Fig. 3 is an end view, and Fig. 4 is an enlarged plan view showing the manner in which rods or heavy wires are assembled to form the legs.

The pallet has a deck portion formed of longitudinally-extending wires or rods 6 to which are welded transversely-extending wires 7. Stiffening rods 8 are welded to the undersides of the wires 7. The wires 6, 7 and 8 together form a truss that will effectively resist bending under loads carried by the deck. The deck wires may suitably be #2 gauge, certain of the wires being bent to curved form as shown at 10—11 to not only stiffen and strengthen the deck at such locations but also to avoid exposed sheared ends of the wires at those points, as shown more clearly in Fig. 1.

Base strips 13 extend transversely of the deck and are formed of wires 14, 15 and 16 which are welded together in mesh form. Longitudinally-extending base strips 17 are formed of wires 18, 19 and 20 welded together in superposed relation. The ends of the wires 18 and 20 are bent to a common plane as at 21, so that they can be entered between the upper wires 14 and the lower wires 16 of the adjacent strips 13 and welded thereto, as shown more clearly in Fig. 1. The corners of the base strips 13 will be curved as at 22 and 23, to give a smooth corner finish, as at 10 and 11.

2

The legs are each formed of rod-like elements 25 bent to somewhat C-form. These may suitably be of #4-0 gauge. The leg elements 25 are shown as arranged in groups of four, but obviously other multiples could be used. The elements of each group are welded together at their vertical mid portions, for a vertical distance of approximately three inches, the laterally-bent upper and lower ends of the leg elements being welded to the deck and the base strips, respectively.

The extended upper and lower portions of the legs serve to stiffen and brace the deck and the base strips against bending or deformation under loads, and the compactly-arranged vertical portions of each group of leg elements results in little obstruction to the ends of lifting forks that are entered between the deck and the base, and furthermore, there will be tendency for the lifting fork or the pallet to be pushed sidewise as by a glancing force, in case the ends of lifting forks impinge directly against the legs, thereby reducing danger of injury to the legs.

While the drawing shows simply a pallet, it will be understood that the pallet deck can be used in connection with crates having their side and end walls connected to the deck, as shown for example in my application Ser. No. 697,507, filed September 17, 1946, or in my application Ser. No. 726,687, filed February 5, 1947.

30 I claim as my invention:

1. A pallet having a deck and a base, and legs interposed between the deck and the base and welded thereto at their upper and lower ends, the legs each comprising a plurality of upright rod-like elements arranged in group formation and with their mid portions welded together, the upper and lower ends of said elements being extended in various generally horizontal directions and welded to the adjacent surfaces of the deck and the base, respectively.

2. A pallet having a deck and a base, and legs interposed between the deck and the base, the legs being of rod-like form, with their upper ends bent to extend in horizontal directions and welded to the deck, the lower ends of the legs being secured to the base.

3. A pallet having a deck sheet formed of wires in relatively crossed relation and welded to one another, the wires at the corners of the deck being extended and bent to curved form, in a plane parallel to the plane of the sheet.

4. A pallet having a deck sheet formed of wires in relatively crossed relation and welded to one another, base strips of welded wire mesh, and legs connecting the base strips to the deck sheet, the

wires at the corners of the deck and the base strips being extended and bent to curved form, in planes parallel to the planes of the deck and the base strips.

5. A pallet comprising a deck, leg members supporting the deck, base strips extending in parallelism with one another, and each comprising upper and lower series of parallel wires with an intermediate series of wires crosswise thereof and welded thereto, and other base strips of wire mesh form extending laterally of the first-named strips, and with certain of their wires projected between said upper and lower series of wires and welded

thereto, the lower ends of the legs being welded to the base strips.
